[57] CLAIM

The ornamental design for a noisemaker, as shown and described.

DESCRIPTION

FIG. 1 is a perspective view of a noisemaker showing my new design;

FIG. 2 is a front elevational view thereof, the rear, top and bottom, being identical;

FIG. 3 is a side elevational view thereof, the opposite side being identical; and,

FIG. 4 is a cross-sectional view thereof, taken in the direction of the arrows along line 4—4 in FIG. 2.
